ADJUSTMENT FOR ALIGNMENT OF ROAD OR SIMILAR FORMS

Filed Sept. 25, 1929

Inventor

Jacob B. Rogers,

N.E. Gee

Attorney

UNITED STATES PATENT OFFICE

JACOB BRUMBAUGH ROGERS, OF ALTOONA, PENNSYLVANIA

ADJUSTMENT FOR ALIGNMENT OF ROAD OR SIMILAR FORMS

Application filed September 25, 1929. Serial No. 395,105.

This invention relates to the construction of concrete roads, walks, or similar structures wherein a plurality of adjustable forms are used to align the sides thereof, and the primary object of this invention is to provide an adjustable form that is susceptible of being readily aligned to suit the surface of the ground over which the concrete walks or roads may be built.

10 Another object of this invention is to provide positive means of adjusting the forms where the top of the form may be thrown in or out to suit the required conditions for vertical alignment, together with means for locking the forms in any desired fixed position.

A further object of this invention is to provide the form with a U shaped yoke, which is adapted to fit against the side and bottom flange of the form, each side of the yoke having a plurality of aligned perforations which coact to secure the locking means.

With these and other objects in view, which will become more readily apparent as the nature of the invention is better understood, the same consists of the novel construction, combination and arrangement of parts as will be hereinafter fully pointed out, illustrated and claimed.

30 It will be quite readily understood by those skilled in the art to which this invention belongs, that the same is susceptible of various changes and modifications without departing from the spirit or scope of the invention, but a practical and preferred embodiment of the invention is shown in the accompanying drawings in which:

Fig. 1 shows a perspective assembly view of my improved adjustable road form.

40 Fig. 2 shows a plan and edge view of one of the locking plates which is shown in position in Fig. 1 of the drawings.

Fig. 3 shows a plan and edge view of the intermediate locking key which passes through the central perforation of the yoke, shown in position in Fig. 1 of the drawings.

Fig. 4 is a front elevational view of the form yoke, also shown in position in Fig. 1 of the drawings.

Fig. 5 shows a side elevational view of the yoke shown in Fig. 4.

Fig. 6 shows a plan view of a modified arrangement for obtaining the same adjustment as is readily obtained with the device shown in Fig. 1 of the drawings.

Fig. 7 shows the side elevation of the parts shown in Fig. 6 of the drawings.

Fig. 8 shows an end elevation of the parts shown in Fig. 7.

Similar reference numerals refer to similar parts throughout the several figures of the drawings.

In carrying out this invention in its most practical form, I provide an L shaped channel section designated in its entirety by the numeral 10, wherein the horizontal leg of the L forms the base, 11, of the form, while the outside of the vertical leg, 12, forms the surface against which the concrete mixture rests until it is sufficiently set to support itself.

The top, 13, of the form is bent back at right angles to the vertical surface, 12, and the edge, 14, thereof is turned downward such as to give a greater safety measure when handling the form.

The yoke, shown in Figs. 4 and 5 of the drawings and designated in its entirety by the numeral 15, is formed in a substantially U shaped section, having flanges, 16, at the top turned outward at right angles to the body portion, 17, of yoke, and adapted to be securely fastened to the side, 18, of the vertical web, 12, as illustrated in Fig. 1 of the drawings.

The yoke, 15, is further provided with a plurality of outward projecting flanges, 19, each of which is securely fastened to the surface, 20, of the horizontal leg, 11, as clearly illustrated in Fig. 1.

The yoke, 15, is still further provided with an outwardly projecting flange, 21, which is struck up from the bottom of the U shaped yoke and is also secured to the face, 20, of the horizontal leg of the form flange, 11.

The yoke, 15, is further provided with a plurality of rectangular slots, designated by the numerals 23 and 24, one of these slots, 23, is positioned above the horizontal center line of the yoke while the other slot, 24, is positioned

below the line and in each of the slots a key, 25, is neatly fitted, as illustrated in Fig. 1 of the drawings. The keys, 25, are each provided with a diagonally positioned rectangular slot, 26, as illustrated in Fig. 2 of the drawings.

The yoke 15, is still further provided with an intermediate locking key, 28, which co-acts with a vertically disposed locking pin, 29, which passes down through the central opening, 30, of the yoke, 15, through each of the diagonally disposed rectangular slots, 26, positioned in each of the keys, 25, and thence into the ground, or similar foundation at the bottom.

Having aligned the form through the function of the keys, 25, the yoke, 15, and the locking pin, 29, the key, 28, is then driven into position, thus locking the rod, 29, in its position in each of the slots, 26, in the keys, 25.

Should it be desired to re-align the form, the key, 28, is first removed, thus permitting the form to move with reference to the rod. 25 Should the top key be then driven from left to right, the top of the form will be thrown in toward the road and vice versa, after which the locking key, 28, is again placed in position.

30 As a further means of shifting the form 10, on the rod, 29, I have shown an alternate method, which employs a worm shaped cam shaft, 31, the cam surface of which co-acts with the rod, 29, and shifts the form in or out 35 depending upon the direction of rotation of the cam. The cam in this alternate method of alignment is positioned in a yoke, 32, which is secured to the vertical wall of the form, as shown in Figs. 7 and 8 of the drawings. Duplicate keys, 28, are illustrated in position in 40 Figs. 7 and 8, and serve to shift the top of the form in or out and to lock the same in position.

Having thus described my invention, what 45 I claim and desire to be secured by Letters Patent is—

1. A metallic road form having an L shaped formation, a substantially U shaped yoke fitted into the interior of the L, a plurality of 50 slots in the yoke, keys positioned in the slots and means for locking the keys in position in the slots.

2. A metallic road form having a relatively long longitudinal leg section, a vertical 55 form section, a top section positioned at right angles to the vertical form section and parallel with the horizontal base section, a U shaped yoke positioned against the vertical section and the horizontal section, a plurality 60 of vertically aligned slots positioned in the sides of the U shaped yoke, keys positioned in each of the slots, a vertical rod co-acting with each of the keys and means for locking the keys against the rod.

65 3. An adjustable U shaped metallic road

form, a U shaped yoke positioned on the body of the form, a plurality of key slots in the sides of the yoke, an intermediate slot, positioned between and parallel with the said key slots, a key having an inclined locking pin engaging surface, a locking pin co-acting with the locking key, rectangular keys positioned in the key slots, diagonally disposed slots positioned in the keys, means for shifting the top and the bottom of the form through the position of said keys with reference to the locking pin.

4. In combination with a metallic road form, a U shaped yoke positioned on the form, a worm shaped cam positioned in the yoke, means for rotating the cam, a plurality of keys for shifting the position of the top and bottom of the form and a locking rod positioned on the cam within the yoke.

In testimony whereof I affix my signature.

JACOB BRUMBAUGH ROGERS.
